(57) **CLAIM**

The ornamental design for a valve assembly, as shown and described.

DESCRIPTION

FIG. 1 is a top, front, and right side perspective view of a valve assembly embodying our new design.

FIG. 2 is a front view thereof.

FIG. 3 is a rear view thereof.

FIG. 4 is a right side view thereof.

FIG. 5 is a left side view thereof.

FIG. 6 is a top view thereof.

FIG. 7 is a bottom view thereof.

FIG. 8 is a top, front, and right side perspective view of a valve assembly embodying our new design.

FIG. 9 is a front view thereof.

FIG. 10 is a rear view thereof.

FIG. 11 is a right side view thereof.

FIG. 12 is a left side view thereof.

FIG. 13 is a top view thereof.

FIG. 14 is a bottom view thereof.

FIG. 15 is a top, front, right side perspective view of a valve assembly embodying our new design.

FIG. 16 is a front view thereof.

FIG. 17 is a rear view thereof.

FIG. 18 is a right side view thereof.

FIG. 19 is a left side view thereof.

FIG. 20 is a top view thereof; and,

FIG. 21 is a bottom view thereof.

The broken lines shown in the figures are for the purpose of illustrating portions of the valve assembly and form no part of the claimed design.

The references to "left," "right," "front," "rear," "top," and "bottom" in the figure descriptions are not meant to require certain in-use orientation; the valve assemblies, valve housings, connectors with conduit, and connectors according to the claimed design may be used in any orientation.
